VICTOR AMEDÉE HOUDAILLE, OF PARIS, FRANCE.

Letters Patent No. 96,116, dated October 26, 1869.

IMPROVEMENT IN BUNGS.

The Schedule referred to in these Letters Patent and making part of the same

To all to whom it may concern:

Be it known that I, VICTOR AMEDÉE HOUDAILLE, of Paris, in the Empire of France, have invented a new and improved "Metallic Bung," and I do hereby declare that the following is a full and exact description thereof, reference being had to the accompanying drawings, and to the letters of reference marked thereon.

The metallic bungs herein mentioned are intended as a substitute for those in present use, the advantages being, first, that they allow no escape of the compressed air, which invariably occurs with the old system, or what are in present use, no matter how well they may be contrived or fixed; and secondly, that they are more economical, in that they last out several barrels or vats, and at the same time preserve the quality and strength of the liquid therein contained.

The accompanying drawings will clearly elucidate my system, which consists of two essential parts, that is to say, first, the body A, (see Figure 1, which represents a bung of this description in its entirety, and a section of which is shown by Figure 2;) and secondly, of the cap or plug B.

The body consists of a socket, with exterior denticulations or grooves P, so that when the bung is once fixed in the barrel or vat, having previously dipped it in resin or other glutinous matter, it adheres so tenaciously to the barrel that the grooves P effectually prevent its removal without taking the barrel to pieces, the closure being so hermetical that it prevents the smallest quantity of air passing between the body and the wood of the barrel.

The interior of the body is furnished with screw-threads V, for receiving the screw of the head or plug V. This latter is of one single piece, shown in Figure 3, the upper part, which, in the drawing is square, but may be made of any other polygonal form, admitting of the adaptation of a key for removing or fixing it, as desired.

The upper part of the plug B may be made as in

Figure 4, in which case it is turned by means of a small metal shaft passed through the opening o.

Below the flange D is placed a leather or India-rubber washer, C, to prevent the passage of air into the vessel.

The plug represented in figs. 3 and 4 is intended for use while the barrels are being moved, and is replaced by that represented by Figure 5 when it is intended to draw off the liquid. This double plug is screw-cut at the lower part, V", for fitting the screw V.

This is also supplied with a washer, c, below the flange D, serving to intercept any passage of air into the interior of the barrel or vat.

The upper part has a screw fitting in the screw-threads V", arranged inside the crown. (See Figure 6.)

The double plug, fig. 5, is bored down its centre e its whole length, so as to give to the barrel all the requisite pressure of air for drawing off the liquid.

The head, fig. 6, has in its centre a small cylindrical tube, with a rim at the lower part, shown in Figure 7, and serving to maintain the end of the India-rubber or gutta-percha tube employed for conducting the air necessary for producing the requisite pressure.

By the foregoing description, it will be observed that my system of bung advantageously replaces those in present use, and does away with the opening or vent for admitting the air, and thus preserving the barrels or vats; and experience has proved that beer especially is improved by the adoption of my system, as there is no loss of air, and consequently the liquid does not become flat, and preserves all its strength and quality.

What I claim, and desire to secure by Letters Patent, is—

The system of metallic bung hereinbefore described, and illustrated by the accompanying drawings.
